UNITED STATES PATENT OFFICE.

WILLIAM J. BITTER, OF TOLEDO, OHIO.

ROSETTE FOR HARNESS.

SPECIFICATION forming part of Letters Patent No. 339,849, dated April 13, 1886.

Application filed January 28, 1884. Renewed March 12, 1886. Serial No. 195,041. (No model.)

To all whom it may concern:

Be it known that I, WILLIAM J. BITTER, a citizen of the United States, residing at Toledo, in the county of Lucas and State of Ohio, have 5 invented new and useful Improvements in Rosettes for Harness-Bridles, of which the following is a specification.

My invention relates to improvements in rosettes for harness-bridles, and has for its 10 object to simplify the construction and cheapen the production of the rosette without detracting from its strength, durability, and attractiveness. I attain these objects by the construction and relation of parts illustrated in 15 the accompanying drawings, in which—

Figure 1 is a face view of the rosette mounted on the bridle. Fig. 2 is a view of the same with the front cap-plate removed, showing the interior. Fig. 3 is an edge view. 20 Fig. 4 is a back view, and Fig. 5 is a cross-section showing the parts and their relation to each other, like letters referring to like parts throughout the several views.

A represents a section of the headstall, and 25 B a section of the brow-band, of an ordinary bridle.

C is the front ornamental cap-plate, to be pressed up or punched out so as to represent any form or configuration desired, having 30 three tangs or clinches, c c c, on the edge of its flange.

D is the back plate, having a flange thrown up on its edge.

E is a wire loop, by means of which the rosette is fastened to the bridle. It is passed 35 through the plate D and clinched on the inside, as shown in E E, Fig. 2.

Having thus described the parts of the invention, the manipulation of placing the rosette in proper position on the bridle and securing it there is as follows: The brow-band 40 B is placed in proper position, so that the headstall passes through its loop, the wire loop or staple E is placed over the brow-band

B, and the plate D is then pressed onto the 45 ends of the staple E and the ends E E clinched down, as shown in Fig. 2. The ornamental cap-plate C is then placed on and over the back plate, D, pressed down closely, and the clinches 50 c c c turned down against the back of the plate D, and the operation is completed.

I am aware that prior to my invention rosettes have been made and used having a wire staple passed through a back plate and clinched down, the said plate having a flange 55 on the inside edge of which there is a screw-thread to receive a threaded ring seamed to an ornamental front plate. I do not therefore claim such an invention, broadly, in its combination; but

What I do claim as my invention, and desire to secure by Letters Patent, is—

1. The harness-rosette composed of the back plate having an upturned peripheral flange, the loop having its ends passed through said 65 plate and bent to secure the loop and plate together, and a front plate having a depending peripheral flange fitting around the flange of the back plate, and having a projecting portion thereof bent onto the outer face of 70 the back plate to hold the parts together, substantially as described.

2. The harness-rosette composed of the back plate having an upturned peripheral flange, the loop having its ends passed through said 75 plate and bent to secure the loop and plate together, and the front plate fitting against the flange of the back plate and provided with depending tangs bent into the outer face of the back plate to hold the parts together, 80 substantially as described.

In testimony whereof I have hereunto set my hand in the presence of two subscribing witnesses.

WILLIAM J. BITTER.
